UNITED STATES PATENT OFFICE.

RUDOLF M. OSTERMANN, OF CHICAGO, ILLINOIS, ASSIGNOR TO LOCOMOTIVE SUPER-HEATER COMPANY, OF NEW YORK, N. Y., A CORPORATION OF DELAWARE.

COMBINED SUPERHEATER AND ECONOMIZER.

1,225,846.

Specification of Letters Patent. Patented May 15, 1917.

Application filed November 24, 1916. Serial No. 133,202.

To all whom it may concern:

Be it known that I, RUDOLF M. OSTERMANN, a citizen of the German Empire, residing in the city of Chicago, county of Cook, and State of Illinois, have invented new and useful Improvements in a Combined Superheater and Economizer, of which the following is a specification.

My invention concerns a superheater of the well known flue tube type, having superheater pipes or elements inclosed in enlarged flue tubes, in combination with an economizer or feed water heater having pipes through which the feed water to be heated is caused to flow, said pipes being inclosed in the same enlarged flue tubes which contain the superheater elements.

It is the object of my invention to provide a combined superheater and economizer, as just referred to, in which a larger amount of heat shall be abstracted by the water and steam system of the boiler than would be possible were either the superheater or the feed water heater used separately or even were they to be combined in one boiler with superheater element and feed water element in separate flue tubes. In other words, it is the object of my invention, speaking generally, to provide a combined superheater and economizer of the type specified and of a superior efficiency.

My invention is applicable to flue tube boilers of various types but is intended particularly for use in connection with locomotive boilers.

My invention will be better understood by referring to the accompanying drawings in which Figure 1 represents a vertical longitudinal section, taken approximately through the region indicated by the line 1-1 of Fig. 2, of so much of a locomotive boiler structure as may be necessary to illustrate my invention; Fig. 2 represents a transverse sectional elevation taken along the line 2-2 of Fig. 1; Fig. 3 represents a partial horizontal section taken along the line 3-3 of Fig. 1; Fig. 4 is a perspective view of a superheater element and an economizer element showing the relation which they mutually bear when in place in a flue tube; Fig. 5 is a view, similar to Fig. 2, showing an arrangement of my invention having a modified form of economizer ele-

ment; Fig. 6 is a sectional plan view along the line 6-6 of Fig. 5; and Fig. 7 is a vertical section taken along the line 7-7 of Fig. 5.

Referring to the drawings, the boiler 1 is of usual type with front flue sheet 2 and smoke box 3. In the flue sheet 2 is arranged a plurality of enlarged flue tubes 4 arranged in horizontal and vertical rows in the usual way. A different arrangement of the flue tubes may, however, be employed. Besides these enlarged flue tubes, other flue tubes (not shown) of smaller size may also be employed as usual.

Arranged transversely across the smoke box above the flue tubes is a steam header 70 comprising a distributing chamber 5 for saturated steam and a collecting chamber 6 for superheated steam, these chambers being connected to alternated parallel disposed branches 7 and 8 for saturated and superheated steam respectively. The saturated steam collector 5 is connected with the steam dome of the boiler by a main inlet pipe 9 in the usual way and main outlet pipes (not shown) connect the superheated steam collector 6 to the steam chests of the engine. Other forms of steam header may be utilized within the spirit of the invention and claims.

Each enlarged flue tube contains a superheater element 10 comprising two pipes in the lower part of the flue tube extending nearly the full length of the same and two other pipes lying in the upper part of the flue tube and extending forwardly from the rear end of the lower pipes about half the length of the flue tube. These four tubes are connected together in series by suitable unions and the free ends of the full length tubes are bent upwardly and connected to adjacent branches 7, 8, of the main steam header in the usual way.

A superheater element, as just described, having two of its four pipes extending approximately the full length of the flue tube and the remaining two of its four pipes extending forwardly from the rear end of the other tubes approximately one half of the length of the flue tube, has been found by experience and study to be a very desirable type of element in respect to securing an efficient absorption and utilization of the hot flue gases. This will be readily ap-

iated when it is remembered that the percentage of heat transferred from the flue gases to the steam within the superheater unit will increase with the difference of temperature between the flue gas and the steam, and also that the temperature of the gases flowing through the flue is continually decreasing from fire box to smoke box so that that part of the superheater unit nearer to the fire box is more effective than that part nearer to the smoke box; and that, further, with the steam flowing through the superheater units with considerable velocity, a certain amount of pressure is lost in friction and that this loss of pressure will depend upon the length of the path through which the steam must travel in the superheater unit. It must further be remembered that this loss of steam pressure is, under certain conditions of locomotive operation, opposed to the development of maximum horse power in the engine cylinders.

The above considerations indicate that the path of the steam should be shortened as much as possible consistently with the maintenance of proper heat transfer and that, furthermore, as much of the superheater unit as possible should be as near the fire box as possible. The type of superheater element shown in the drawings and above described, and commonly known as a "half return" element, has been found to best satisfy the above enumerated conditions. In respect to the decrease of total superheater element heating surface caused by shortening the unit, the superheating effect has also been decreased, but it has been found, nevertheless, that under certain conditions of locomotive operation, the gains resulting from this shortening of steam path more than compensate for the accompanying loss of heat absorbing surface.

The adoption of the half return superheater unit has, however, entailed two very serious disadvantages. The first disadvantage results from the fact that as soon as the flue gases, coming in the direction of the arrow from the fire box, reach the end of the short leg of the superheater element, they at once spread out owing to the greater free cross section of the flue tube, thus slowing up in velocity and thereby permitting to be deposited upon the walls of the flue tube and upon the superheater pipes in the bottom of the flue tube a large amount of solid material carried in suspension by the flue gases. The free cross section of the flue tube will therefore be rapidly filled up, thus lessening the draft, and at the same time the heat absorbing quality of the flue walls and of the superheater pipes will be diminished by reason of the non-conducting coating of solid material.

The other disadvantage is thermal and results from the fact that the facility of heat transfer from gas to steam increases rapidly with the velocity with which the gas flows past the heating surfaces. The gas velocity being greatly decreased after it has passed the end of the short leg of the superheater element, a much smaller amount of its heat is given up to the water in the boiler surrounding the flue tube and to the steam contained in the forward part of the longer leg of the superheater element.

In order to obviate the two disadvantages just mentioned and at the same time to usefully employ the largest possible amount of heat obtainable from the flue gases, I fill the space which has been left vacant in the upper part of each flue tube by shortening the upper leg of the superheater element, with a suitable feed water or economizer element 11 having its ends connected to a suitable economizer header. Thus, referring to the drawings, this space in the upper part of each flue tube which has been gained by shortening the upper leg of the superheater element is occupied by a flat U-shaped loop, preferably of pipe having the same size as that of which the superheater element itself is made. The outer ends of each loop are bent upwardly and rearwardly as indicated at 12 and connected with suitable openings formed in the front of narrow economizer headers 13 which are arranged transversely in front of the tube sheet and immediately above each horizontal row of flue tubes. Preferably there are two sets of economizer headers, one occupying one side of the smoke box and the other the other side of the smoke box. The inner ends of these headers are abutted together at the center and provided with suitable lugs 14 which are bolted together so as to assist in the support of the headers.

A pair of inlet and outlet pipes 15, 16, are vertically disposed on each side of the boiler and connect respectively to the economizer header chambers. The arrangement is such that the feed water entering through pipe 15 passes through the several feed water elements successively and leaves by pipe 16.

The free ends of each economizer element may be fastened to the economizer headers in any manner usual for superheater elements. Thus, in the embodiment herein described each end is spherically shaped and adapted to fit a correspondingly shaped opening in the front of the header. A clamp bar 17 and bolt 18 hold each pair of ends in position so as to provide a steam and water tight joint.

It will be obvious from the above that the hot flue gases will pass through the flue tubes exactly as they would were these tubes occupied by full length superheater elements since, so far as the pipe space with-

in the flue tube is concerned, this is filled to the same extent and in the same way as it would be were there only the usual full length superheater element and no economizer unit. It is true that there is a physical break in the pipes where the end of the short leg of the superheater element rejoins the end of the economizer element but the effect of this upon the flow of the flue 10 gases is substantially *nil*.

In Figs. 5 to 7 inclusive, I show a modified form of my invention. This modification differs substantially from that shown in Figs. 1 to 4 inclusive only in that each single 15 U-shaped economizer element is replaced by a pair of economizer elements of special form. Owing to this special form of economizer element, a corresponding change in the structure of the headers to which said 20 economizer elements connect is required.

Similar parts in Figs. 5 to 7 inclusive are designated by the same reference characters as are used in Figs. 1 to 4 inclusive.

Referring now to Figs. 5, 6 and 7, each 25 economizer element 11' comprises an outer tube 19 and an inner spaced concentric tube 20, the outer ends of which are suitably connected to chambers in headers 13' which are 30 arranged transversely to the boiler and immediately in front of the rows of flue tubes. The other end of each inner tube is open and extends to within a short distance of the closed end of the outer tube. Preferably the inner tube is provided with an outer 35 spiral 20' of thin sheet metal, the outer edges of the spiral extending to the wall of the outer tube.

Each header 13' comprises a series of linearly disposed chambers 23 lying immediately adjacent to the front tube sheet, a 40 second series of similar chambers 24 lying just forward of the first series and displaced horizontally with reference thereto, and a third chamber 25 at the extreme front of 45 and extending entirely across said header. The outer tubes 19 extend through the rear wall of the header into the chambers 23 while the inner tubes 20 extend through the chambers 23 and through the rear wall of 50 the series of chambers 24. The front chamber 25 and the chamber 23 which lies adjacent to the center of the boiler are connected together. A main inlet pipe 15' opens into the outside chamber 23 and a 55 main outlet pipe 16' opens into the outer end of the front or third chamber 25. The partitions which go to make up the chambers of the first and second series are so disposed, relatively to one another, that water 60 entering the inlet pipe 15' will enter the outer economizer element 11' between its inner and outer tube and, following the path determined by the spiral 20' between said tubes, will enter the end of its inner 65 tube remote from the tube sheet and pass-

ing therethrough will enter the outer chamber of the second series. Hence it will pass into the inner tube of the second economizer element and, reaching the end of said element remote from the tube sheet, will return through the space between the inner and outer tubes of the element to enter the second chamber of the first series. It then enters the space between the outer and inner tubes of the third economizer element, returning through the inner tube to the second chamber of the second series and so on until it finally emerges from the space between the inner and outer tubes of the last economizer element of the row at the center of the boiler, from whence it passes through the passage provided to the front chamber 25 and out through the outlet pipe 16'.

I have found the spiral wound in the 85 space between the inner and outer tubes of the economizer elements advantageous inasmuch as it causes the water which is to be heated to pass between the tubes more slowly than would otherwise be the case 90 and thereby gives the water an opportunity to absorb a large amount of heat. This spiral may, however, be omitted if desired.

It will be noticed that, in the construction just described, two of the concentric tube 95 types of economizer element replace the single U-shaped economizer element of the form shown in Figs. 1 to 4, *i. e.*, each of the last described economizer elements replaces a single leg of the element of the first described form.

While I have described the short leg of the superheater element as having one half the length of the longer leg, variations from this proportion may be used without departing from the invention. Such variations merely vary the degree in which the superheater and economizer units perform their functions with respect to one another and will be dictated by the particular requirements which it may be desired to fulfil.

It is also not essential that the longer leg of the superheater should lie at the bottom of the flue tube and the economizer unit at the top. These positions might be reversed or the parts referred to might be arranged one on one side and the other on the other side of the flue tube. Or the planes of the loops of said two parts might be given some intermediate positions.

Still other forms of header and other arrangements of the economizer inlet and outlet pipes may, of course, be employed within the spirit of the invention and of the following claims.

This application is a continuation in part of my earlier application entitled "Combined superheater and economizer" filed in the United States Patent Office July 8, 1916, Serial No. 108,127, the forms of the inven- 125

tion disclosed in Figs. 1 to 4 inclusive of the drawings having been disclosed and claimed in said earlier application.

I claim—

5. 1. In a boiler provided with a plurality of enlarged flue tubes, the combination with each of some of such tubes, of a superheater element comprising four serially disposed pipes, two of which are in one plane and extend substantially the entire length of the flue tube while the other two are in a parallel plane and extend from the rear ends of the longer pipes to a point well to the rear of the smoke box, an economizer element in the same plane as the shorter leg of the superheater element and extending from the end of said shorter leg to the smoke box, means for passing steam from the boiler through the superheater elements and means for passing water through the economizer elements to the boiler.
10. 2. In a boiler provided with a plurality of enlarged flue tubes, the combination with each of some of such tubes, of a superheater element comprising four serially disposed pipes, two of which are in one plane and extend substantially the entire length of the flue tube while the other two are in a parallel plane and extend from the rear ends of the longer pipes to a point well to the rear of the smoke box, an economizer element comprising a single loop of two pipes in the same plane as the shorter leg of the superheater element and extending from the end of said shorter leg to the smoke box, means for passing steam from the boiler through the superheater elements and means for passing water through the economizer elements to the boiler.
15. 3. In a boiler provided with a plurality of enlarged flue tubes, the combination with each of some of such tubes, of a superheater element comprising four serially disposed pipes two of which are in one plane and extend substantially the entire length of the flue tube while the other two are in a parallel plane and extend from the rear ends of the longer pipes to a point well to the rear of the smoke box, an economizer element comprising a single loop of two pipes in the same plane as the shorter leg of the superheater element and extending from the end of said shorter leg to the smoke box, a steam header having a collecting and distributing chamber for saturated and superheated steam respectively, the ends of the superheater elements being connected in parallel to said chambers, and a transverse economizer header for each row of economizer elements adjacent to the ends of the flue tubes said header having independent chambers and the ends of the economizer elements being connected between chambers so as to constitute one continuous series, the end chambers of the series being respectively joined to a source of water supply and to the boiler.
20. 4. In a boiler provided with a plurality of enlarged flue tubes, the combination with each of some such tubes, of a superheater element comprising four serially disposed pipes two of which are in one plane and extend substantially the entire length of the flue tube while the other two are in a parallel plane and extend from the rear ends of the longer pipes to a point well to the rear of the smoke box, an economizer element comprising a single loop of two pipes in the same plane as the shorter leg of the superheater element and extending from the end of said shorter leg to the smoke box, means for passing steam from the boiler through the superheater elements, an economizer header in the smoke box provided with a plurality of independent chambers the chambers being adapted to be connected serially by the economizer elements, and means for introducing water into one end chamber of the series and for transferring water from the other end chamber to the boiler.
25. 5. In a boiler provided with a plurality of enlarged flue tubes arranged in horizontal rows, the combination with each of a plurality of tubes in said rows, of a superheater element comprising four serially disposed pipes two of which lie in one horizontal plane and extend substantially the entire length of the flue tube while the other two are in a parallel plane and extend from the rear ends of the longer pipes for substantially half the length of the flue tube, an economizer element comprising a single loop of two pipes in the same plane as the shorter leg of the superheater element and extending from the end of said shorter leg to the smoke box, a steam header having a collecting and distributing chamber for saturated and superheated steam respectively, the ends of the superheater elements being connected in parallel to said chambers, and a transverse economizer header for each row of economizer elements adjacent to the ends of the flue tubes said header having independent chambers and the ends of the economizer elements being connected between chambers so as to constitute one continuous series, the end chambers of the series being respectively joined to a source of water supply and to the boiler.

In testimony whereof I have hereunto set my hand.

RUDOLF M. OSTERMANN.
